UNITED STATES PATENT OFFICE.

GEORGE E. ADAMS, OF NEW BRITAIN, CONNECTICUT.

DESIGN FOR A SOCKET MEMBER FOR DETACHABLE FASTENERS.

SPECIFICATION forming part of Design No. 28,346, dated March 8, 1898.

Application filed January 24, 1898. Serial No. 667,832. Term of patent 3½ years.

To all whom it may concern:

Be it known that I, GEORGE E. ADAMS, a citizen of the United States, residing at New Britain, in the county of Hartford and State 5 of Connecticut, have invented and produced a new and original Design for a Socket Member for Detachable Fasteners, of which the following is a specification, reference being had to the accompanying drawings, forming 10 a part thereof.

In the drawings, Figure 1 is a plan view of a socket member for detachable fasteners having my new design. Fig. 2 is a sectional view on the line $x-x$ of Fig. 1. Fig. 3 is a perspective view of the same.

As shown in the drawings, the leading or 15 material feature in my design consists of the

scalloped base-flange A, a central raised annular projection B, the topsurface of said projection having a series of annular grooves, 20 and ribs C, surrounding the central aperture D. The ribs and grooves give the top of the projection a corrugated appearance, and each of the scallops of the base-flange has a central aperture, as shown.

Having thus described my invention, what I claim as new is—

A design for a socket member of a detachable fastener herein shown and described.

GEORGE E. ADAMS.
